FLEXIBLE CLOSURE

Filed March 5, 1925

Fig. 1.

Fig. 2.

Fig. 3.

A technical line drawing of a garment, likely a jacket or coat, shown from the front. The garment features a zipper closure at the bottom center. Above the zipper, there is a belt with a central buckle and two side buckles. The belt is secured to the garment with four visible buttons. The garment has two large pockets on the lower front. The drawing is annotated with various numbers and letters, such as '10' at the top center, '40' and '45' at the top right, '12', '13', '35', '30', '31', 'R', '10', '15', '37', '38', '21', '41', '1', '36', and '21' on the right side. The garment is depicted with a hatched pattern on the lower half, suggesting a different fabric or texture.

RALPH H. BINNS, OF PITTSBURGH, PENNSYLVANIA, ASSIGNOR OF ONE-HALF TO
EDWARD H. BINNS, OF PITTSBURGH, PENNSYLVANIA.

FLEXIBLE CLOSURE.

Application filed March 5, 1925. Serial No. 13,090.

The present invention relates to an improved pull member for cam sliders of the type employed with flexible strips or stringers of spaced interlocking fastening devices. The present invention consists of a combined pull member and drag or brake lock. The improved member is swiveled for lateral movement and hinged for a limited vertical movement upon the slider. A 10 latch is arranged between the pull member and slider for securing it in closed position and the side edges of the pull member are presented downwardly to frictionally engage the exposed outer faces of the interlocked fastening devices.

In order that the invention may be fully understood it will first be described with reference to the accompanying drawing and afterwards more particularly pointed out in 20 the annexed claims.

In said drawing:

Fig. 1 is a front elevation of a portion of a flexible closure illustrating the present invention applied thereto;

Fig. 2 is a side elevation of the same;

Fig. 3 is a similar view, partly in section, showing the combined pull member and brake raised slightly in position for a downward pull upon the slider;

Fig. 4 is a transverse sectional view taken on the line 4—4 of Fig. 1;

Fig. 5 is a view similar to Fig. 1 with the pull member reversed and extended upwardly for an upward or closing pull upon the slider;

Fig. 6 is a side elevation of the same;

Fig. 7 is a detail transverse sectional view showing the combined hinge and swivel connection of the pull member with the slider; 40 and

Fig. 8 is a view similar to Fig. 2 showing a slight modification.

In the type of flexible closure to which the present invention relates, two flexible 45 strips or stringers 1, 2 are formed at their inner edges with beads or thickened portions 3 upon which are secured interlocking fastening devices.

Each interlocking fastening device is

preferably formed with a U-shaped yoke 50 10 embracing and compressed upon the beaded or thickened edge 3 of a flexible stringer, a narrow neck 12, a forked hook 13, and the opposite riding lugs or shoulders 15. The specific form and operation of 55 the fastening devices of the preferred construction will be more fully understood by reference to the patent of Binns, Binns and De Hart, No. 1,553,499, dated September 15th, 1925.

The operating cam slider is preferably constructed as set forth in the above named patent of a back-plate 20 and a fore-plate 21 mounted in spaced relation upon a binder post 22. The inner faces of the back-plate and fore-plate are provided with controlling grooves 25 separated by a central guide rib 26. The riding lugs 15 of the fastening devices operate in the controlling grooves 25.

30 is a swivel pin mounted to turn freely in the binder post 22 and formed at its outer end with a transversely perforated head 31. 35 is a pull member formed at one end with the separated bearing eyes 36, which are presented upon opposite sides of the swiveled head 31 and are hinged thereto by a transverse pivot pin 37. A centrally curved arm 38 projects from pull member 35 over the swivel head 31 in position to engage the outer face of fore-plate 21 to limit the outward movement of pull member 35 and afford a fulcrum engagement with the slider to control the angular position of the slider upon the interlocking fastening devices. The combined swivel and hinge joint between pull member 35 and the slider is in effect a universal joint connection between these parts.

The end of the pull member 35 opposite its hinge connection with the swivel pin is recessed at 40 to receive a spring snap 41 projecting outwardly from the fore-plate 21 at its lower edge. This spring snap 41 latches the pull member in closed position 45 against the face of fore-plate 21 of the slider.

Pull member 35 is preferably formed

with inwardly presented side walls or flanges 45 that are shaped to fit over the side edges of the slider and frictionally engage the exposed outer faces of the interlocked fastening devices just outside the side walls of the slider. The drag or braking edges of these side walls 45 may be roughened as indicated in Fig. 3 to afford effective frictional engagement with the fastening devices, 10 or these side walls may be definitely notched as shown at 50 in Fig. 8 to actually fit over the exposed yoke ends of the fastening devices and more positively lock the slider against movement. In this modified form 15 shown in Fig. 8, it will be observed that the projections 50 are of proper size and shape to substantially occupy the spaces between adjacent fastening devices.

It will also be observed that the present 20 invention provides a combined pull member and drag or brake for locking the slider upon two series of interlocked fastening devices. Referring to Fig. 3, it will be understood that to move the slider downwardly 25 for unlocking the fastening devices, a pull in the direction of arrow x while exerting slight outward pressure in the direction of arrow y will effectively move the slider downwardly over the locking devices with 30 the least resistance. For interlocking the fastening devices, the pull member 35 is moved from the position shown in Fig. 3 into reversed position as shown in Figs. 5 and 6, the swivel connection with the slider permitting this reversal. An upward pull in 35 the direction of arrow x' and slight outward pressure in the direction of arrow y' , will move the slider upwardly to cause the interlocking of the fastening devices. In 40 both these unlocking and locking movements, it will be understood that the engagement of the arm 38 with the outer face of the slider will give an effective leverage control of the angular position of the slider upon 45 the fastening devices to prevent "digging in" or improper interference between the parts.

While the fulcrum member 38 is shown 50 projecting centrally from the hinge of the pull member 35, it is obvious that the same result can be accomplished by forming a suitable heel or projection from any part of the hinge of the pull member to limit the outward movement of the pull member upon 55 the slider and afford the leverage control of the slider when it is operated.

The provision of the universal joint connection of the pull member with the slider, whereby the hinged end of the pull member 60 swivels or rotates laterally upon the slider is so arranged that the hinged end of the pull member will not project beyond the sides of the slider, so that there will be no chance of interference or engagement with

the stringers or material to which the stringers are attached. 65

I claim:

1. In a flexible closure or fastener, the combination of flexible strips or stringers having spaced interlocking fastening devices, and an operating slider embracing and sliding upon said fastening devices, with a combined pull member and drag or brake having universal joint connection with said slider. 70

2. In a flexible closure or fastener, the combination of flexible strips or stringers having spaced interlocking fastening devices, and an operating slider embracing and sliding upon said fastening devices, with a pull member pivotally mounted upon said slider and formed with side flanges arranged to project over the slider sides and engage 80 said fastening devices.

3. In a flexible closure or fastener, the combination with flexible strips or stringers having spaced interlocking fastening devices, and an operating slider embracing and sliding upon said fastening devices, with a pull member pivotally mounted upon said slider and formed with side flanges which project over the edges of the slider in position to frictionally engage the exposed faces of the fastening devices to constitute a drag or brake lock. 95

4. In a flexible closure or fastener, the combination with flexible strips or stringers having spaced interlocking fastening devices, and an operating slider embracing and sliding upon said fastening devices, with a pull member having a combined vertical and horizontal pivoted connection with said slider. 100

5. In a flexible closure or fastener, the combination with flexible strips or stringers having spaced interlocking fastening devices, and an operating slider embracing and sliding upon said fastening devices, with a swivel pin mounted in said slider, and a pull member hinged to said swivel pin. 105

6. In a flexible closure or fastener, the combination with flexible strips or stringers having spaced interlocking fastening devices, and an operating slider embracing and sliding upon said fastening devices, with a swivel pin mounted in said slider, and a pull member having a limited hinged connection with said swivel pin to provide for free lateral movements of the pull member into positions above and below said pin and for limited movements toward and away from said slider. 115

7. In a flexible closure or fastener, the combination with flexible strips or stringers having spaced interlocking fastening devices, and an operating slider embracing and sliding upon said fastening devices, with a pull member having a combined swivel and 120

hinged connection with said slider, and a fulcrum arm projecting from said hinge in position to engage the face of the slider for limiting the hinge movement of the pull member and affording leverage control of the angular position of the slider.

having spaced interlocking fastening devices, and an operating slider embracing and sliding upon said fastening devices, with a pull member reversibly swivelled upon said slider and formed with a fulcrum arm projecting from the swivel in position to engage the face of the slider.

8. In a flexible closure or fastener, the combination with flexible strips or stringers

RALPH H. BINNS.
